United States Patent Office

Des. 210,440
Patented Mar. 5, 1968

210,440

KNIFE

John W. Latham, London, England, assignor to Wilkinson
Sword Limited, London, England, a British company

Filed Feb. 3, 1967, Ser. No. 5,685

Term of patent 14 years

(Cl. D95—3)

FIG. 1.

FIG. 2.

FIG. 3.

FIG.4.

FIG.5.

FIG. 1 is a perspective view of the front, top and one side of a knife showing my new design;

FIGURE 2 is a perspective view of the rear, underneath and other side thereof;

FIGURE 3 is an elevational view of the side seen in FIGURE 1;

FIGURE 4 is an elevational view of the side seen in FIGURE 2; and

FIGURE 5 is a plan view thereof.

The dominant features of the design reside in the handle shown in full lines, the conventional blade being shown in broken lines.

I claim:

The ornamental design for a knife, as shown and described.
